ATTORNEY

UNITED STATES PATENT OFFICE.

LEARCUS H. JACOBS, OF CARTHAGE, ARKANSAS.

HITCH RACK.

1,417,385.

Specification of Letters Patent. Patented May 23, 1922.

Application filed March 17, 1919. Serial No. 283,094.

To all whom it may concern:

Be it known that I, LEARCUS H. JACOBS, a citizen of the United States, residing at Carthage, in the county of Dallas and State 5 of Arkansas, have invented new and useful Improvements in Hitch Racks, of which the following is a specification.

This invention relates to a rein or line holding device, and the principal object of 10 the invention is to provide means for receiving the free ends of the reins or lines when the driver wishes to free his hands thereof and to prevent the lines dropping under the horse's feet.

15 Another object of the invention relates to means for permitting the lines to be easily and quickly placed in the holder and for increasing the gripping action by the pull of the horses on the lines.

20 The invention also consists in certain other features of construction and in the combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the 30 several views, and in which:—

Figure 1 is a view of a wagon with my invention thereon.

Figure 2 is a front view of the device.

Figure 3 is a plan view thereof.

35 Figure 4 is a view of the supporting member with the gripping members removed.

Figure 5 is a detailed view of one of said members.

40 In these views, 1 indicates the supporting member, which is of T-shape, and has its stem provided with a pair of holes 2, said holes passing through the stem at right angles to each other. These holes are to receive the securing means, such as a bolt or 45 the like for connecting the device with the vehicle body. By means of the two holes

50 3 at each end thereof on which the gripping members 4 are rotatably supported. As shown, said gripping members are eccentrically mounted on said shafts and I prefer to form each member of semi-circular form in

55 cross-section and to provide a laterally extending part 5 at each end thereof each of

said parts being provided with an opening to receive the shaft. The rounded part of the semi-circular part is corrugated lengthwise so as to provide a gripping surface. 60 Each of said semi-circular portions are also provided with longitudinal openings 6 to reduce the weight of the parts and to save material. A coil spring 7 is located on each shaft and has one end secured thereto and its 65 upper end secured to a part of the gripping member to hold said members with the semi-circular members in engagement with each other. As shown in the drawing, the end of the coil spring passes through a slot 8 in 70 said semi-circular portion into the opening 6, and engages a bar 9 which holds the end of the spring in engagement with said member. The upper ends of the members are rounded and are also inclined downwardly 75 towards the roughened surfaces so as to direct the lines into the space between the members. The movement of the members caused by the springs are limited by a wedge-shape projection 10 placed on the cross-piece 80 of the supporting member midway its ends. Thus the springs will move the members until their lower edges engage said projection when further movement will be prevented. In this position the roughened surfaces of the members are in contact. It will 85 thus be seen that when the driver wishes to leave the vehicle or desires to let go of the lines he simply passes the lines over the upper ends of the members and pulls the 90 lines rearwardly to take up the slack. The rounded and inclined ends will direct the lines between the gripping surfaces of the members and the drawing on the lines rearwardly will partly rotate the members to 95 permit the lines to pass between the same. When the lines are released the springs will cause the members to move in the opposite direction to grip the lines between them. Any pull on the lines by the horses will tend 100 to tighten the grip of the members on said lines.

What I claim is:—

A hitch rack of the class described comprising a T-shaped supporting member having a stem provided thereon and having a pair of folds formed therein arranged at right angles to each other, means for securing the device to the vehicle body, an upright shaft carried by the cross piece of the 110 supporting member at each end thereof, gripping members rotatably supported on

the latter, said members being of semi-circular formation in cross section and provided with a laterally extending part at each end thereof and having openings provided therein to receive the shaft, each of said semi-circular portions having longitudinal openings therein, a coiled spring located on each shaft and having one end secured thereto and its upper end secured to a part 5 of the gripping members to hold said members with the semi-circular members, the end

of the coiled spring passes through a slot formed in the semi-circular portion into longitudinal openings, a bar supporting the end of the spring and engaging said openings to hold the spring in engagement with said members, a wedge-shaped projection provided on the cross piece of the supporting member midway its ends for limiting the movement of said members. 15

20 In testimony whereof I affix my signature.
LEARCUS H. JACOBS.
